United States Patent Office.

P. ROSENBLATT, OF GREENVILLE, TENNESSEE.

Letters Patent No. 61,874, dated February 5, 1867.

IMPROVED DOOR AND WINDOW-SASH FASTENER.

The Schedule referred to in these Letters Patent and making part of the same.

TO ALL WHOM IT MAY CONCERN:

Be it known that I, P. ROSENBLATT, of Greenville, in the county of Greene, State of Tennessee, have invented new and useful Improved Fastener for Door and Window Sashes; and I do hereby declare that the following is a full, clear, and exact description thereof, which will enable others skilled in the art to make and use the same, reference being had to the accompanying drawings, forming a part of this specification.

The present invention relates to a new and improved fastener for doors and windows, more especially, which fastener is exceedingly cheap to manufacture, simple in construction, and very efficient and reliable in operation, as will be obvious from the following detail description of the same. In the accompanying drawings—

Figure 1 is a perspective view of the fastener.

Figure 2, a view showing it as applied to a door; and

Figure 3, a view showing it as applied to a window sash.

Similar letter of reference indicate like parts.

A, in the drawings, represents my improved fastener, embraced in the present invention, which is made of a narrow plate or bar, B, of metal or other suitable material, tapering in thickness and coming to a sharp edge at one end, C, and at the other provided with a series of sharp prongs or teeth, a, that project out therefrom in a direction at right angles, or nearly so. D, a handle or knob secured to the end of the plate B, where provided with prongs, a, but upon the opposite side thereto, the object of which handle is to enable the fastener to be easily removed or withdrawn from the sash or door, according to which it is applied.

In using my improved fastener for a window sash, it is inserted by its tapering end in and between the sash and the window frame, as plainly shown in fig. 3, with its prongs or teeth a toward the window frame, when slightly inserting the said teeth in such window frame, it is plain to be seen that in an attempt to raise the sash frame my fastener will necessarily prevent it, which, to more fully insure, I provide the side of the plate B, which comes in contact with the sash frame when used as a fastener thereto, with a series of corrugations, c, extending in the direction of its length, by the sharp edges, d, of which it is made to be more firmly and "fast." When my improved fastener is used for a door, it is placed by its tapering end under the door, between it and the sill, and in the position shown in fig. 2, with its teeth or prongs a inserted or embedded in the sill, whereby, as is obvious, it is rendered impossible to open the door; the fastener, in both the case of the window sash and door, being easily removed by means of its handle or knob D. Although I have herein described my invention as a fastener for a window sash, it may be employed to advantage as a supporter thereto, as is obvious without any further or more particular explanation.

I claim as new, and desire to secure by Letters Patent—

The fastener A, consisting of a plate or bar B, tapering in thickness at one end, and at the other provided with a series of teeth or prongs a, substantially as described for the purposes specified.

I also claim the corrugations c, of the fastener plate B, substantially as and for the purpose specified.

The above specification of my invention signed by me this 14th day of July, 1866.

P. ROSENBLATT.
